ARTHUR J. BOYNTON, OF CHICAGO, ILLINOIS, ASSIGNOR TO H. A. BRASSET, INC., OF CHICAGO, ILLINOIS, A CORPORATION OF ILLINOIS

METHOD FOR HANDLING SINTER

Application filed March 18, 1925. Serial No. 15,962.

This invention relates to a new and improved method for handling material and more particularly, to a method adapted to screen and cool the product of a sintering process.

The invention has particular application to the handling of sinter made by processes well known in the art, the sintering having for its object the agglomerating of metalliferous ores and flue dust in its fine state of division. In some sintering processes the method also serves to eliminate from the ores by combustion, sulphur or other combustible substances. Usually the primary object of the sintering process is to increase in size the pieces of ore which are subsequently used in the charge of a metallurgical furnace.

In one sintering process as now carried out the metallic charge, generally in a fine state of division, is spread upon the grate bars of a so-called sintering pan mixed with a definite percentage of fuel. This fuel may be contained in the charge as a result of previous introduction into a furnace, as in the case of blast furnace. Flue dust, or the fuel may be added for the purpose of sintering. After the spreading of the charge, the fuel is ignited and combustion is maintained by means of a current of air drawn down through the charge from the upper surface through interstices in the grate bars which support the charge, by a suction draft. At the conclusion of the process, the resulting sinter is an agglomerated mass in a more or less plastic state.

The pan is then inverted so that the sintered material falls on an inclined surface below the pan, part of which surface is usually provided with a screen or bars for the purpose of removing from the product any portion of the sinter which is in too fine a state of division to adapt it for use. The remainder of the sinter passes down an inclined surface without retardation into a freight car or other receptacle. This dumping of the sinter on the inclined surface and the subsequent motion of the sinter over screens and into the car has the disadvantage of severe breakage, and abrasion of the plastic sinter, which reduces it in size and thus in part de-

feats the object of the sintering process. Also, the car or other receptacle is subject to damage by the residual heat in the sinter.

A further objection to this method lies in the fact that the screening which is possible to effect by rapid motion over a steeply inclined screen is not suitable for the objects of the sintering process since the rapid motion of the sintered products prevents the elimination of fines, except on a basis of screening so coarse that much sintered product suitable for use is allowed to pass through the screen with the fines. Also, this practice provides no means for reducing pieces of sinter which are objectionably large.

It is an object of the present invention to provide a new and improved method for handling sinter whereby the sinter may be air cooled, crushed to reduce large pieces and screened at a slow rate of speed whereby the production of fines is reduced and the elimination of fines more efficiently effected.

It is a further object of the invention to provide a method of this character whereby the sintered mass is air cooled before being crushed, or screened, whereby its hardness is increased and the production of fines reduced.

It is an additional object to provide a method of this character which is simple and adapted for commercial application to existing sintering apparatus.

It is also an object to provide a new and improved method of handling sinter by which the sinter is air cooled before crushing, crushed and screened, the fines produced being reduced in quantity by the cooling preliminary to the crushing.

Other and further objects will appear as the description proceeds.

I have illustrated a preferred form of apparatus somewhat diagrammatically in the accompanying drawings, in which—

Figure 1 is a side elevation, and

Figure 2 is a front elevation of the apparatus.

Referring to the drawings,—

The sintering pan 11 is supported on trunnions 12 about which it may be rotated to dump the sinter into the hopper 13. The

lateral walls of this hopper are air tight and its bottom is formed from a plurality of downwardly inclined overlapping plates 14, which are separated sufficiently to permit the passage of air into the hopper, but to prevent discharge of the sintered product. The passage 15 extends from the upper end of the hopper and leads to any source of draft, such as a stack.

10 The lower end of the hopper 13 is closed by the gate 16 operated by lever 17. The feed roller 18, which is divided into a plurality of compartments 19, is located below the gate 16. Below the feed roller 18 are located 15 the pair of crusher rolls 20 and 21. These rolls discharge onto the screen 22, which has been shown in the form of a bar screen or grizzly. Below the screen 22 is located a hopper 23 having the bottom 24 similar in 20 construction to the bottom 14 of the hopper 13. The discharge end of the hopper 23 is controlled by gate 25.

Below gate 25 is located the screen 26, which may be vibrated electrically or mechanically by any known process. Material passing over the screen 26 is discharged through chute 27 into car 28. Material passing through the screen 26 is discharged through spout 29 into receptacle 30. Material passing over the bar screen 22 passes down the upper surface 31 of the chute 27 into the car 28.

In the operation of the apparatus, the sintered material is dumped from the sintering pan into the hopper 13 and the heat of the material induces a draft through the bottom 14 and up the stack 15. This flow of air is distributed through the material by the nature of the bottom and serves to cool and 40 harden the sinter. The gate 16 is opened to discharge the material as desired and the flow is further controlled by the feed roller 18, which may be rotated at any desired speed suitable for the purpose. The material passing through the rollers 20 and 21 has the 45 larger pieces reduced to a suitable size.

The material passing over the bar screen 22 has the larger pieces fed directly to the car 28. The smaller pieces and the fines 50 which are too small for use pass through the screen 22 and are further cooled by air coming through the bottom 24. This material is passed over the screen 26 at a rate of flow controlled by the gate 25. As has been stated, 55 the screen 26 may be vibrated to give a more efficient screening action. The screen 26 eliminates the fines and the remaining material is discharged to the car.

This apparatus serves to cool the material 60 thus hardening it and minimizing the breakage of the material into fines. The cooling also serves to prevent damage to the car or other receptacle. The crusher rolls prevent the passage of material in larger pieces than 65 is desirable. The gates and feed roll control

the rate of passage of material, so that it may be caused to pass over the screens slowly in a thin layer. The screens may therefore, be of a proper size to eliminate only the undesirable fines and all of the usable material 70 will be passed to the car.

It is to be understood that the showing of the drawings is somewhat diagrammatic, and I contemplate such changes and modifications as come within the spirit and scope of 75 the accompanying claims.

I claim:

1. The method of handling sinter which comprises air cooling the material and passing it at a controlled rate of flow over screens 80 to remove the fines.

2. The method of handling sinter which comprises air cooling the material, crushing it to reduce the larger pieces and passing it at a controlled rate of flow over screens to 85 remove the fines.

3. The method of handling sinter which comprises air cooling the material, crushing it to reduce the larger pieces, passing the material over a coarse screen to remove the 90 larger remaining pieces, and passing the material which passes through the first screen over a second screen to remove the fines.

4. The method of handling sinter which comprises air cooling the material, crushing it to reduce the larger pieces, passing the material over a coarse screen to remove the 95 larger remaining pieces, and again air cooling the material which passes through the first screen over a second screen to remove the 100 fines.

Signed at Chicago, Illinois, this 5th day of February, 1925.

ARTHUR J. BOYNTON.
